UNITED STATES PATENT OFFICE.

LEO PUNGS, OF BERLIN-CHARLOTTENBURG, GERMANY, ASSIGNOR TO C. LORENZ AKTIENGESELLSCHAFT, OF LORENZWEG, BERLIN-TEMPELHOF, GERMANY.

SIGNAL-SENDING APPARATUS IN WAVE TELEGRAPHY.

Application filed August 23, 1921. Serial No. 494,571.

(GRANTED UNDER THE PROVISIONS OF THE ACT OF MARCH 3, 1921, 41 STAT. L., 1313.)

To all whom it may concern:

Be it known that I, LEO PUNGS, a citizen of Germany, residing at Berlin-Charlottenburg, Germany, have invented certain new and useful Improvements in Signal-Sending Apparatus in Wave Telegraphy (for which applications were filed in Germany September 27, 1913, and December 7, 1913, Patents Nos. 291,132 and 298,532), of which the following is a specification.

This invention relates to a method for the sending of signals in the wave telegraphy by means of high frequency machines which is based upon the known property of coils with iron cores to be able to vary their inductivity within wide limits. It is known to provide such a coil with two or more separate windings of which the one conducts a high frequency current and the other the continuous current for the production of the superposed magnetic induction. This coil can thus be used in simple manner as variometer by merely regulating the inductivity by variation of the continuous current without any alteration upon the high frequency side.

This method can be applied according to this invention in connection with high frequency machines in varying the conditions of resonance of the syntonizing circuits of the machine when the wave lengths or the syntony are altered.

The method is explained by the connection-arrangement shown on the only figure of the drawing and which is based upon a Goldschmidt machine.

In the figure *a* and *b* are stator and rotor coils of an alternator, *a* designating the stator connected with the antenna, and *b* the rotor of the machine with the necessary syntonizing circuits consisting of capacity and self-induction. In the first syntonizing circuit the iron core *d* with the high frequency winding *e* and with the continuous current winding *f* is inserted whilst the continuous current is controlled by the key *h* across an adjustable resistance. In this case the coil alters thus the syntonization for the fundamental frequency and thereby the supply of energy from the machine in the radiated energy of the antenna. Comparatively small desyntonizations are sufficient to bring the energy to zero.

According to the method described the signal-sending in wave telegraphy by variation of the wave lengths or tuning is produced in such a manner that at the variation of the inductivity of a coil with iron core by superposed magnetic continuous current inductions the resonance conditions of the syntonizing circuit of high frequency machines are altered.

The method possesses however an inconvenience in so far as considerable losses can occur in the iron core of the coil at high frequency, said losses consuming a part of the high frequency energy. This phenomenon becomes specially unfavorable when the coil is inserted for instance in a syntonizing circuit of a high frequency machine, system Goldschmidt, as in this case already little losses make considerably worse the supply of energy from the number of useful periods.

It has been found that the losses in the iron can be made to disappear almost completely if the continuous current induction is made so high that the iron is practically saturated. As example the following statements are given:

A wound iron ring from sheet metal band of 0.05 millimeter thickness produces at a wave length of 7000 meters and with a determined intensity of current without continuous current induction an equivalent loss-resistance of 500 ohms. As soon as the iron core is completely saturated by a continuous current magnetization which corresponds with an ampere winding number of approximately 100 per centimeter, the loss resistance sinks at equal intensity of high frequency current to about 1 to 2 ohms. This value corresponds almost to the true resistance-losses in the high frequency winding so that the iron losses disappear owing to the extraordinarily small alternating current induction in the iron. The coefficient of self induction of the coil sinks at the same time to about $\frac{1}{10}$ of its value when there is no continuous current magnetization.

The invention is based in its further development on this experience in improving the method. The number of windings and the current of the winding for the superposed continuous current induction are selected so that the iron is practically fully

saturated, whereupon the oscillation-circuit in which the iron coil is inserted is syntonized under the conditions mentioned.

The signal-sending is effected in such a manner that while the signals are sent the continuous current has its full value and the iron core is fully saturated, whilst at the time of the intervals between the signals the continuous current is either completely cut 10 out or the magnetization is brought under the knee so that besides the desyntonization by variation of the inductivity the radiated energy is made to disappear further by the extraordinary increase of the resistance-value of the coil.

The method is of special advantage for high frequency machines with multiple increase of the frequency by syntonizing circuits (according to Goldschmidt's principle 20 or with utilization of frequency transformers or the combination of the two). As already mentioned with Goldschmidt's machine the losses in the syntonizing circuit must be as small as possible as these circuits ought to be really short-circuited. The utilization of the coils with iron cores for sending the signals causes very high losses and therefore would not be useful. Only by the principle of the full saturation of the 30 iron core at the times of the consumption of energy it has become possible to apply this method to high frequency machines of the type mentioned.

There are however still other advantages 35 obtained. The iron core can be inserted in the circuit of the fundamental frequency (the smallest frequency) of the machine instead of being laid on the antenna so that in this manner the losses are still further 40 reduced when in the period of the radiation of energy the iron core is practically fully saturated. As the syntonizing circuits, specially with large machines, contain only small self-induction, the self-induction 45 of the coil with iron core can be dimensioned very small in order to obtain the required degree of desyntonization which means smaller dimensions and little losses.

It has in fact been possible to reduce, 50 with the application of the method described and with insertion of the coil in the circuit of the fundamental frequency of a machine, the losses so far that almost no difference could be ascertained in the sending of energy whether a coil with highly saturated iron core or a coil of equal self-induction without such iron core was used. By cutting off the continuous current for 55 the magnetization of the iron core coil the radiation of energy of the antenna could 60

be brought almost to zero so that the signal sending could be executed in the simplest manner.

When a machine with static frequency converters is used it is also of great advantage to lay the coil with iron core into the circuit of the fundamental frequency in order to make the losses as small as possible.

I claim:—

1. In a signal sending apparatus for wave telegraphy, a high frequency machine having a plurality of syntonizing circuits of different frequencies, a coil having an iron core electrically connected with said circuits, and means associated with said core whereby the coil may be subjected to superposed magnetic continuous current induction, thereby varying the inductivity of the coil and changing the conditions of resonance of the syntonizing circuits. 70 75 80

2. In a signal apparatus for wave telegraphy, an antenna circuit, a high frequency machine having a plurality of syntonizing circuits of different frequencies and connected with said antenna circuit for radiating signals, a coil having an iron core interposed in said circuits and adapted to normally maintain the antenna current at a minimum, and means for subjecting the coil to superposed magnetic continuous current induction during the sending of signals, said means being adapted to cause substantially complete magnetic saturation of the iron core and thereby substantially eliminate 90 95 magnetic induction of high frequency in the iron core and permit maximum flow of current in said antenna circuit.

3. In a signal sending apparatus for wave telegraphy, an antenna circuit, a high frequency machine having a plurality of syntonizing circuits of different frequencies and connected with the antenna circuit for radiating signal energy, a coil having an iron core connected with a machine circuit 100 having a lower frequency than the antenna circuit, and means whereby the coil may be subjected to superposed magnetic continuous current induction during signal sending intervals and thereby simultaneously change the conditions of resonance of 105 said syntonizing circuits and antenna circuit.

In testimony whereof I have signed this specification in the presence of two witnesses.

LEO PUNGS.
